UNITED STATES PATENT OFFICE.

WILLIAM MACGLASHAN, OF SOUTH BEND, INDIANA, ASSIGNEE TO THE STUDEBAKER CORPORATION, OF SOUTH BEND, INDIANA, A CORPORATION OF NEW JERSEY.

SAFETY-SWITCH FOR MOTOR-VEHICLES.

1,094,798.

Specification of Letters Patent. Patented Apr. 28, 1914.

Application filed February 5, 1913. Serial No. 746,327.

To all whom it may concern:

Be it known that I, WILLIAM MACGLASHAN, a citizen of the United States of America, residing at South Bend, St. Joseph county, State of Indiana, have invented certain new and useful Improvements in Safety-Switches for Motor-Vehicles, of which the following is a specification.

This invention relates to an electric switch, particularly adapted for use in connection with electrically driven road vehicles. Such vehicles are commonly provided with a switch independent of the controller by means of which the circuit may be opened when for any reason the controller cannot be conveniently operated or refuses to act. It is also used to open the circuit when the machine is idle to prevent leakage or accidental starting and for safety in overhauling, and to prevent unauthorized use of the machine the switch is provided with a removable key. The difficulty commonly experienced in connection with the operation of such switches, is due to the fact that owing to ignorance or inadvertence on the part of the operator the controller will sometimes be moved from neutral with the circuit open at the switch or the machine stopped by opening the circuit at the switch and later, with the controller in position to pass a considerable current through the armature, the switch will be thrown in and the circuit closed. Under these circumstances the machine starts suddenly and often unexpectedly and serious accidents have resulted. On the other hand if the machine is heavily loaded so its inertia cannot be overcome instantly the motor is apt to be burned out for the back electro-motive force and the electrical resistance in the motor are slight; and the flow of current is excessive with a correspondingly great tendency to burn out the motor.

The switch which is the subject of this invention is constructed for the purpose of overcoming this difficulty, and by its use accidental starts and burning out of the motor under the circumstances described are rendered practically impossible.

Described in general terms, the device consists of automatic means for locking the switch out of contact so that the circuit is held open together with means connected to and moving with the controller for rendering the locking means on the switch inopera-

tive when the controller is at neutral, so that in the neutral position, and only in the neutral position of the controller, can the switch be operated to close the circuit. Thus it is rendered impossible, once the switch is thrown out, to pass a current through the motor with the controller in the position of full speed forward or backward, or half speed backward or forward, or in any position other than the neutral position.

Described more specifically, the device in its preferred form consists of a pivoted switch for making and breaking the circuit which may be provided with a movable key for engaging the switch, a spring-actuated bolt on the switch, a fixed retainer engaging the bolt as the switch is oscillated, and holding it in retracted position, the retainer being discontinued or apertured at one point forming a socket to admit the bolt and lock the switch out of contact, means for closing the socket to exclude the bolt, and means connected to the controller to operate the closing means to close the aperture when the controller is at neutral.

In the accompanying drawings I have illustrated a safety switch constructed in accordance with the preferred form of my invention.

Of these drawings, Figure 1 is a plan, the switch handle, and guiding arc, being cut away for simplicity in illustration showing diagrammatically the motor, charging plug, batteries and connections. Fig. 2 is a side elevation; Fig. 3 is a front elevation; Fig. 4 is a vertical, central section taken at right angles to Fig. 2; and Fig. 5 a general view of the switch, the electric controller and mechanical control taken from the side of the vehicle.

Referring to the drawings by numerals, the device includes a switch lever 1 pivoted at 2 on a support 3, attached to a base 4 of suitable insulating material upon which are mounted stationary terminals or contacts 5 adapted to coöperate with moving contacts 6 carried by the switch and the contacts 6 are separated by an arc, central at 2, of less extent than that of the arc separating the terminals 5 so charging plug and motor cannot both be in circuit at the same time. Of the four contacts 5, two are for running and the others for charging. The support 3 is electrically connected to the batteries C

by suitable connections inclosed in covering or cable 7, the forward stationary contact 5 being connected to the charging plug A, by wires 8' inclosed in a suitable cable or conduit 8, and the rear contact 5 being similarly connected to the motor B by wires 9' inclosed in covering or cable 9.

The switch lever 1 is centrally apertured in the direction of its axis at 10. Mounted 10 within the aperture or longitudinal bore 10 is a removable key 14 which extends through the slot in the cover plate 15, the key being provided with a suitable finger grip to be used in moving the switch. Below the key 15 aperture is an aperture 11 restricted at its upper end and enlarged at the lower end of the lever to form a shoulder 12 and open at the bottom of the lever. The shoulder 12 forms the upper abutment for a compression spring 13 in the enlarged lower end of the aperture 11 and a sliding pin 17 in this aperture has a shoulder 18 upon which the lower end of the spring rests. The upper end of the pin is reduced at 16 20 above the shoulder to enter the restricted portion of the aperture 11 and the reduced portion 16 of the pin is inclosed within the coils of the spring. Thus the constant tendency of the spring is to force the pin 17, 25 which is herein referred to as a sliding bolt, downward so as to cause the lower end 16 to protrude from the lever, but the support 3 is provided with a retaining member 20 elongated in the direction of the arc, swung 30 by the lower end of the lever 1 as the latter is oscillated, and this retainer serves to hold the sliding bolt normally retracted within the lever, or at least to hold it out of locking position as hereinafter described. While 35 the retainer 20 conforms substantially to the arc swung by the lower end of the switch, it is in fact somewhat steeper than that arc, the ends being higher and the center portion lower than in the case of an arc of a true 40 circle struck about the center on which the lever swings, and at its center the retaining member 20 is provided with a vertical socket 21 sufficient in cross-section to receive and admit the lower end 16 of the pin 17. Thus 45 the socket serves, under certain conditions to be hereinafter described, to lock the switch in central position as shown in Fig. 2, with the moving contacts 6 free of the fixed contacts 5, so that the circuit is opened. 50 This aperture extends downward into the support 3, and at its lower end is restricted forming a shoulder 22. Within the aperture 21 is a sliding pin 23 which normally rests with its shoulder 24 on the shoulder 22 of the support. But this pin 23 is actually controlled as to its position by means of a cam 25 connected to the control cylinder 26, see Fig. 5, to rotate therewith, and the cam is so placed relatively to the controller and is so shaped that in the neutral

position of the latter and the lever 27, the upper end of the pin 23 is on a level with the surface of the retainer 20 and the socket or hole 21 is closed, so the lower end 17 of the sliding bolt cannot enter its socket and lock the switch with the control at neutral.

In Fig. 5 I have shown what may properly be termed a mechanical controller for actuating and operating the rotary member of the electric controller 26. This consists of a head lever 27 guided in a U-shaped slot 28 having a neutral point at 29. This lever is pivoted at 30 and jointed at 31 to swing laterally so that it can follow the U-shaped slot. On each side of the lever 27 are crank arms 32 provided each with a lateral slot open toward the lever 27. These crank arms are connected by rods 33, one to the arm 34 of the shaft 35, the other to the arm 36 of the same shaft substantially at right angles with the arm 34. By swinging the lever 27 laterally, it may be thrown out of engagement with one of the cranks 32 and into engagement with the other. In engagement with one crank, the lever 27 acts on the upper arm 34, and when moved laterally into engagement with the other crank, it operates on the lower arm 36. By this means the effect of the dead points of the arms 34, 36 is avoided, and in connection with one crank 32, the shaft 35 is rotated forward and back through an arc of 90° more or less on one side of its neutral position corresponding to the neutral position of the lever 27 and controller 26, and in connection with the other crank 32, the shaft 35 is rotated through a corresponding arc on the other side of neutral. In the neutral position of the controller, the arm 27 is in the rearward end of the slot 28 and resting against the wall 29 of that slot as shown in Fig. 5, and at the same time the high point of the cam 25 bears against the lower end of the pin 23 closing the socket 21. Thus in the neutral position of the controller the switch is free to be thrown as desired, either for charging or running, and not only is this true, but during running the switch is free to be thrown out. However when once thrown out it is locked and cannot be thrown in until the control is returned to neutral. It will be apparent from the shape of the retainer 20, as described, the retainer being made steeper than the arc swung by the end of the switch lever, that when the switch is once disconnected, i.e., the contacts 6 freed from the contacts 5, the switch will seek its central position, being moved by the cam action of the spring-propelled bolt 17 and the inclined faces of the retainer 20. In the open position of the switch, if the controller is out of neutral, the bolt will drop into the socket 21 and the switch will become locked, and when once so locked the switch cannot be thrown.

The bolt 17 must be withdrawn before the switch can be moved and this can only be accomplished by moving the controller to neutral, thus the machine cannot be started or the motor burned out by accidental closing of the switch.

The description relates to the details of the device but the essential features which I desire to claim are:

16. 1. In an electrically driven motor vehicle, a controller, a switch for making and breaking the circuit independently of the controller, the switch being in the form of a swinging lever carrying a contact member, 15 a spring-pressed latch inclosed within the lever, and not within the control of the operator, for locking the switch out and holding the circuit open, and a member connected to and actuated by the controller for rendering said locking means inoperative when the controller is at neutral, the switch when closed being free so that it can be thrown open at any time.
2. In an electrically driven motor vehicle, 25 a controller, a switch for making and breaking the circuit, automatic means for locking the switch out of contact, holding the circuit open, means for centering the switch and bringing it into locking position when it is thrown out of contact, and means automatically rendering said locking means inoperative when the controller is at neutral.
3. In an electrically driven motor vehicle, 25 a controller, a pivoted switch for making and breaking the circuit, a spring-actuated bolt on said switch, a fixed retainer engaging the bolt as the switch is oscillated and holding it in retracted position, the retainer being apertured to release the bolt 40 and receive it to hold the switch in inoperative position when the circuit is open, means for closing the aperture in the retainer, and means connected to the controller and to the closing means for actuating the latter to close the aperture.
4. In an electrically driven motor vehicle, 45 a controller, a pivoted switch for making and breaking the circuit, a spring-actuated bolt on said switch, a fixed retainer engaging the bolt as the switch is oscillated and holding it in retracted position, the retainer being apertured to admit the bolt to hold the switch in inoperative position with the circuit open, means for closing the aperture in the retainer, and means connected to the controller and to the closing means for actuating the latter to close the aperture when the controller is in neutral position.
5. In a motor vehicle, a controller, a pivoted switch for making and breaking the circuit, a spring actuated bolt carried by said switch, a fixed retainer engaging the bolt as the switch is oscillated and holding it in retracted position, the retainer being apertured to release and admit the bolt, 60 and hold the switch in inoperative position with the circuit open, a sliding pin for closing the aperture in the retainer and a cam connected to the controller and engaging the pin to place the same on a level with the surface of the retainer when the controller is in neutral position, closing the aperture and freeing the switch.
6. In an electrically driven motor vehicle, 75 a rotary controller, a switch for making and breaking the circuit, a locking member, means tending to advance said member, a fixed retainer for holding the locking member in retracted position, a socket in the path of the locking member into which it 80 normally advances when in registration therewith, holding the circuit open, means for closing the socket to exclude the locking member, and means moving with the controller actuating said closing member to 85 close the socket when the control is at neutral.
7. In an electrically driven motor vehicle, 85 a switch for making and breaking the circuit, means for locking the switch open, a controller lever, means connected to the lever for rendering the locking means inoperative when the control is at neutral, means inclosing the switch, a removable key for operating the switch, the inclosing means being slotted to admit the key.
8. In an electrically driven motor vehicle, 90 a switch for making and breaking the circuit, a charging plug, a motor, a storage battery, terminals connected to the charging 100 plug, terminals connected to the motor, means connecting the switch to the battery and contact members on the switch separated by a distance less than that separating the terminals, means for locking the switch in 105 open position, a controller lever, and means connected to the controller lever for rendering the locking means inoperative when the controller lever is at neutral.

Signed at South Bend, Indiana, this 28th day of January 1913.
